BUTLER R. PLATT, OF PLAINWELL, MICHIGAN.

SPRING BED-BOTTOM.

SPECIFICATION forming part of Letters Patent No. 293,077, dated February 5, 1884.

Application filed June 16, 1883. (No model.)

To all whom it may concern:

Be it known that I, BUTLER R. PLATT, of Plainwell, in the county of Allegan and State of Michigan, have invented a new and Improved 5 Spring Bed-Bottom, of which the following is a full, clear, and exact description.

The object of my invention is to provide an improved spring bed-bottom of simple and cheap construction, which shall afford large 10 surface area for the support of the bedding, and which will readily yield to the movements of the body.

Reference is to be had to the accompanying drawings, forming a part of this specification, 15 in which similar letters of reference indicate corresponding parts in all the figures.

Figure 1 represents in plan view the end portion of a spring bed-bottom embodying my improvements, and as made in two folding sections of the frame. Fig. 2 is an end view of 20 the two sections as folded. Fig. 3 is an enlarged longitudinal sectional elevation on line $x x$, Fig. 1. Fig. 4 is a perspective view of a pair of the springs, and Fig. 5 a like view of 25 one of the spring-couplings.

I here represent my springs and couplings as connected to a frame consisting of opposite end bars, a , connected securely to slats b of any suitable length, two frame-sections, $a b$, being 30 here employed for a given width of bed, and hinged together by strong hinges c , so as to fold one section upon the other, as in Fig. 2, for convenient storage or transportation; but for a wider bed three hinged sections may be used 35 and the side sections fold upon reverse sides of the central section, as will readily be understood. The springs d may be coiled in cylindrical or double or single cone shape—preferably the latter form—and to be secured at their 40 apices to the slats b in any suitable manner; and I may make the springs singly and connect them in pairs by a separate cross-bar, e ; but I prefer to coil the springs in pairs from the ends of the same piece of wire, and bend the central 45 portion of the wire so as to form the notches f , in which the hooks of the wire coupling h engage, the notches f in any case being formed in the cross-bar e , where it joins the curving wire of the springs and directly opposite the 50 centers of the bodies of the springs. The coupling h consists of a single piece of wire, first bent downward upon itself at the end, to form

a hook, i , then at a point corresponding to the distance apart one way of the springs d . Wire h is bent downward and around parallel with 55 the first cross-head k , in hook form, as at l , hook l being made of double thickness of the wire by bending the wire sharply at the end of the hook and around closely to the head k to a point about at the center of the head, when 60 the wire is bent horizontally and about at right angles to head k , to form the stem m , making, with head k , a $\square$ outline. The wire h is then bent to either side, to form a second double hook, l' , and also beyond the end of stem m to 65 the opposite side of the stem, to form a third opposite double hook, l' , the wire h being again bent horizontally to form the second stem m in line with the first stem, as shown, and so on in a succession of stems and oppositely-bent 70 double-hook heads for any desired width of frame $a b$, with a single hook, i , at the other extreme side edge of the coupling; and the end hooks, $i i$, may also be formed double by bending the wire back on itself to about the center 75 of the end heads, k , which heads may have hooks formed at the ends of four thicknesses by bending or doubling the wire of the heads twice on itself each side of stems m , which arrangement would give increased sidewise elasticity of the coupling by the opening and closing of the loops; but the one double of wire is considered sufficient for all practical purposes. 80 In this example the coupling is made to connect two adjacent pairs of springs with each other, and the two end pairs to the bed-frame bar a , for which latter purpose I provide the end bar, a , with the fixed staples or eyes o , to be engaged by the hooks of the couplings. The lengths of the heads k and stems m of the 85 couplings h may vary to space the springs d any desired distance apart to accommodate the size of the bed and the degree of elasticity desired, and the coupling heads and stems $k m$ afford a large elastic surface-support to the 90 bedding between the springs d .

To assemble the parts in a complete bed-bottom the springs d are secured to slats b , as the hooks of couplings h are engaged with the staples o of the frame and the notches f of the 95 springs, which may quickly and easily be done; and when the connected springs are weighted the draft or pull of the couplings h on the springs d lengthwise of the bed or in line with

the heads *k* of the couplings will be in a direct line with the centers of the springs *d*, which are thus held in place squarely and their elasticity best utilized; and in sidewise strains on the bed the double loops of wire heads *k* are free to open and close again by their elasticity, thus providing for every condition of strain, and making a bed-bottom well calculated for comfort and durability in use.

10 I am aware it is not broadly new to connect a series of pairs of coiled bed-springs by means of a wire-coupling, it being exemplified in Patent No. 216,057; but my special construction and combination of such parts secures additional vantages that render it superior. Thus, the connecting portion of each pair of springs has two curves or bends, *f*, which serve as points of attachment for the hooks of the coupling, and prevent the said hooks from sliding or slipping laterally when the bed is in use, so that the springs cannot be forced out of due vertical position; and hence the mattress is better supported and rendered more comfortable for the person reposing on it. It also follows that the mattress-cover is subjected to less strain and wear and the springs retain longer their due form and elasticity. The coupling

itself is made with a view to the greatest economy of material and labor consistent with its function, and with especial reference to ease of attachment and detachment, each hook being for this purpose separately adapted for instant connection with and disconnection from the adjacent spring.

Having thus described my invention, what I claim is—

1. As a new article of manufacture, the wire coupling for coiled springs of bed-bottoms, the same consisting of a series of cross-heads, *k*, each having a hook at both ends, and the straight stems, *m*, which are arranged at right angles to said cross-heads and connect them, as shown and described.

2. The combination of the coupling, consisting of cross-heads *k*, having terminal hooks *i*, *l*, &c., and connecting-stems *m*, with the pairs of springs having connecting cross-bar *e* and notches or outward bends *f*, all as shown and described, for the purpose specified.

BUTLER R. PLATT.
